CLAIM

The ornamental design for a backrest for a toilet, as shown and described.

DESCRIPTION

FIG. 1. is a perspective view of a backrest for a toilet, showing our new design;

FIG. 2. is a top view thereof;

FIG. 3. is a front view thereof;

FIG. 4. is a rear view thereof; and,

FIG. 5. is the right side view thereof. The left side view is a mirror image.
